UNITED STATES PATENT OFFICE.

HARRY C. WITT, OF STONEHAM, MASSACHUSETTS.

BOX.

Application filed April 25, 1923. Serial No. 634,455.

To all whom it may concern:

Be it known that I, HARRY C. WITT, of Stoneham, in the county of Middlesex and State of Massachusetts, a citizen of the 5 United States, have invented a new and useful Improvement in Boxes, of which the following is a full, clear, and exact description, reference being had to the accompanying drawings, forming a part of this specification in explaining its nature.

The invention relates to an improved type of box and essentially a display box.

The object of the invention is to make a box out of heavy stock such as cardboard 15 or fibreboard; the parts of the box to be struck from a blank and assembled without the auxiliary means of fastening or joining together customarily employed and in a manner to give strength and serviceability 20 to the box coupled with an attractive form.

The invention can best be seen and understood by reference to the drawings in which—

Figure 1 is a perspective of the box.

Fig. 2 is a section on the line 2—2 of Fig. 4.

Fig. 3 is a vertical median section of the box from front to back, and

Fig. 4 is a section on the line 4—4 of Fig. 2.

1 represents the body of the box and 2 the cover.

The body of the box comprises a bottom 3, back 4, front 5 and sides 6, 6. The back, 35 front and sides are integral with the bottom and turn upwardly therefrom along lines or edges attained by scoring a flat blank, all the parts being cut from the blank by a single operation. The back 4 is preferably turned to lie vertical while the front 5 is 40 preferably turned to lie away from the vertical and inclined slightly toward the back.

The sides 6, 6 are turned to lie between the front and back which overlap the respective ends 7 of the sides and are fastened thereto. The fastening is effected by a tenon 8 on each end 7 of the sides which pass through mortises 9 cut in the adjacent front or back. These tenons fit within the 50 respective mortises with rather a snug fit which is ample to hold the assembled parts together although the application of some adhesive such as shellac is preferably made to each tenon at the time the joint is made.

55 The body of the box may be provided with

any one or more partitions 10 and these partitions are fastened to one another or to the sides, front or other part of the box as desired by simply forming tenons 8' on the end of each partition and passing the 60 same through a mortise 9' cut in the adjacent part.

The cover 2 of the box may consist of simply a flat plate cut from a blank although preferably in the form of a frame surrounding an opening adapted to receive any suitable transparency (not shown). The cover is arranged to overlap the top edges to the front and sides of the body of the box and is hinged to the body of the box in the following manner:—

Projecting from each side of the box at a point inwardly removed from the back thereof is a strap 11 which turns backwardly on an arc. The ends of these straps are passed through mortises 12 cut in an upward extension 4' to the back 4 of the box body. The straps 10 form hinges on which the cover turns, the cover being applied to these straps by passing the straps through slots or mortises 13 formed in the cover before the ends of the straps are fastened to the back extension 4'. The hinge-forming straps 11 are integral with the sides of the box, being cut from the blank with the sides and other parts forming the body of the box.

Having thus fully described my invention, I claim and desire to secure by Letters Patent of the United States:—

1. A box having a body and cover, the body of the box having sides with hinge-forming straps upturned therefrom and the cover having slots through which the straps are passed whereby the cover is hinged to the body of the box.

2. A box having a body and cover, the back of the box having an extension, the sides of the box being provided with hinge-forming straps upturned therefrom and connected to said back extension and the cover having slots therein through which the straps are passed whereby the cover is hinged to the body of the box.

3. A box having a body and cover, the back of the box having an extension with mortises cut therein, the sides of the box having hinge-forming straps upturned therefrom and extended through said mortises in the back extension and the cover

having slots through which the straps are passed whereby the cover is hinged to the body of the box.

4. A box having an integral body struck from a scored blank and comprising a bottom with back, front and sides upturned from said bottom, the back and front being connected to the respective sides by tenon and mortise joints, the back of the body of

the box having an extension with mortises 10 cut therein, the sides of the box having hinge-forming straps upwardly projecting therefrom and extended through said mortises in the back extension and the cover having slots through which the straps are 15 passed whereby the cover is hinged to the body of the box.

HARRY C. WITT.
